UNITED STATES PATENT OFFICE

2,602,278

COTTON-PICKING FINGER

Sam Women Sam, Chicago, Ill.

Application November 2, 1949, Serial No. 125,066

2 Claims. (Cl. 56—32)

1

The invention relates to cotton picking fingers to be used in a cotton picking machine of the suction type.

An object of the invention is to provide a cotton picking finger that picks cotton cleanly by avoiding the necessity to spin the cotton picking finger.

Another object is to provide a cotton picking finger that is durable and inexpensive.

Other objects and advantages become apparent as the description proceeds.

I attain these objects by a device illustrated in the accompanying drawing, in which—

Figure 1 is an axial, sectional view of the cotton picking finger 4 held securely by a rubber fastener 6 in the hole of a external wall 1 of a closed chamber whose air contents is to be continuously exhausted by a suction fan during normal operation, and

Figure 2 is an end view of same.

In Figure 1, there is shown the cotton picking finger 4 comprising a slender resilient, cylindrical tube of fine stainless steel spring wire of circular cross-section, coiled helically, uniformly and closely. The end of the tube 4 is formed into a flange by coiling the wire spirally and closely to form a circular flat flange 2 perpendicular to the axis of said tube 4. The flange 2 is held securely by the receptacle 5 of the soft rubber fastener 6 which is fitted in the hole 7 of the wall 1.

The receptacle 5 is adapted to receive and to hold conveniently, detachably and snugly the flange 2 of the cotton picking finger 4. The cotton picking finger 4 has its other end closed by the hemispherical tip 3 formed by coiling the wire hemispherically and closely. There is barely sufficient opening between the turns of the wire through which air is sucked into the tube of cot-

ton picking finger 4 and thence out of the cotton picking finger 4 through its open rear end.

Since the cotton picking finger 4 does not spin, it can pick cotton cleanly.

5 I claim:

1. In a cotton picking machine of the suction type, a cotton picking finger made of bare wire coiled helically to form a short resilient bare tube having a substantially closed forward end and an open rear end.

2. In a cotton picking machine of the suction type, a cotton picking finger made of bare wire coiled helically to form a short resilient bare tube having a substantially closed forward end and also having a spiral shaped flange at its rear end formed integral therewith, said rear end being open.

SAM WOMEN SAM.
